UNITED STATES PATENT OFFICE.

ELMER E. F. CREIGHTON, OF SCHENECTADY, NEW YORK, ASSIGNEE TO GENERAL ELECTRIC COMPANY, A CORPORATION OF NEW YORK.

PROTECTIVE DEVICE.

1,269,526.

Specification of Letters Patent. Patented June 11, 1918.

Application filed June 8, 1916. Serial No. 102,452.

To all whom it may concern:

Be it known that I, ELMER E. F. CREIGHTON, a citizen of the United States, residing at Schenectady, in the county of Schenectady, State of New York, have invented certain new and useful Improvements in Protective Devices, of which the following is a specification.

My invention relates to protective devices and in particular to devices for rapidly extinguishing an arc produced either by over-voltage or by the opening of a switch of the air break type.

The object of my invention is to provide a novel and improved device for extinguishing arcs that may occur due to over-voltage conditions on a line, or due to the opening of an air break switch under load, and more particularly to extinguish such arcs with great rapidity and without producing detrimental surge conditions on the line.

In devices at present known for extinguishing arcs, such as horn gaps used as lightning arresters or for taking the arc when a switch opens, the arcs are comparatively slowly extinguished. In such devices, the arcs are gradually lengthened and are only finally extinguished by accidental drafts of air producing thereby high frequency high voltage surges on the circuit every time the arc is partially extinguished and reforms. The arcs travel up the horns comparatively slowly and bow out rendering them liable to be easily blown into adjacent phases to cause disastrous short circuit conditions.

The improved and novel device of my present invention I have shown, by way of example, in combination with a disconnecting switch or a switch of the air break type but it is understood that the device may be used by itself as a lightning arrester, the device operating to extinguish the arc in an exceedingly quick time and in a manner which produces no detrimental surges on the line. My novel device or arc extinguisher comprises cooperating horn or arcing members, each horn member forming a closed electrical circuit or closed electrical loop, inductively related to another circuit, such as the circuit through the switch, and constitutes

the secondary circuit of a transformer connected to the conductor on each side of the switch. Each horn member is provided with arcing portions which coöperate to form a 55 horn gap. The horn members have induced therein heavy currents and are so arranged that a very strong magnetic field is produced along their arcing portions in a direction to lengthen and attenuate the arc by causing 60 the craters of the arc to move along the arcing portions of the horn members with great rapidity. In some cases, I use an arc resisting means such as grids or plates along the arcing portion of each horn member or a 65 tubular member such as shown in Fig. 5, by means of which I am able to confine or limit the area in which the arc takes place and thereby prevent it from being blown about and endangering adjacent phases. 70

The novel features which I believe to be characteristic of my invention will be definitely understood in the claims appended hereto; the features of construction and mode of operation will be understood by 75 reference to the following description taken in connection with the accompanying drawings in which Figure 1 shows, diagrammatically, in perspective, my novel and improved protective device or arc extinguisher 80 embodied in a switch connected to a conductor to be protected; Fig. 2 shows a top elevation of my arc extinguishing device; Fig. 3 a front elevation of the device; Fig. 4 a modified form of switch in combination with the arc extinguishing device; and Fig. 5 is a modified form of the arc extinguishing device. 85

In Fig. 1, I have shown, for purposes of illustration, my arc extinguishing device applied to and in combination with an air break switch connected to a line or conductor 1 to extinguish the arc when the switch opens. The switch comprises a pivotally mounted switch member or blade 2 coöperating with a fixed contact member or contact 3 to open and close the switch. A stop 4 is provided to limit the movement of the switch member 2 in its open position. The movable switch member carries an auxiliary 100 contact member or wiper 5 adapted as the switch opens to wipe or slide across the tips

or ends of the arcing portions of the horn members to carry or transfer the arc to the arcing portions of the horn members. The operating mechanism for moving the switch 5 comprises a movable or actuating member 6 pivotally connected to the switch member 2 and carrying a holding block or member 7. Stops 8 and 9 are provided between which the block 7 is movable and which acts to 10 limit the movement of the member 6. The actuating member 6 when moved to close the switch carries the block 7 into engagement with the stop 8 and tensions a spring 10 which is secured at one end to the block 7. 15 The actuating member 6 and hence the switch, is locked in switch closing position, by a latch 11 coöperating with the actuating member 6 and preferably with a lug 12 on the block 7. The operating mechanism is 20 thereby restrained in switch closing position and biased by the spring 10 to move into switch opening position very quickly with a snap action. For moving the latch 11 to release the operating mechanism, I provide 25 a trip coil 13 operative to trip the latch with a hammer blow automatically in response to overload. The latch may also be released at will by means of the operating rod 14. When the latch is released from its 30 engagement with the lug 12, the actuating member 6 moves with a snap action under the tension exerted by spring 10 to open the switch very quickly moving the switch member 2 from engagement with contacts 3 to 35 engagement with the stop 4, and carrying the wiper quickly across the arcing portions of the horn members to transfer the arc to the arcing portion, the actuating member 6 being limited in its movement by the engagement of the block 7 with the stop 9.

Switches of the character which are usually installed outdoors and exposed to the weather, often become inoperative due to accumulations of ice and snow, and to protect my switch under these conditions I mount above the fixed contact 3 and also above the pivotal connection of the actuating member 6 to the switch member 2, protecting shields or umbrellas 15 and 16 respectively which act to prevent the accumulation of ice and snow on the operating parts and to render the switch operative under all kinds of weather conditions. The snap action of the switch member 2 from under its 55 protective shield 14 acts to remove any ice or snow accumulation which may extend into the path of the switch member.

Operatively related to the switch and in position to take the arc produced when the 60 switch opens, I provide my arc extinguishing or attenuating device which acts to extinguish the arc formed as the switch opens, in an exceedingly quick time.

This device comprises two coöperating

horn members 17 and 18 which are preferably located, as shown, immediately above the movable switch member 2. Each horn member is shown as consisting of a continuous rod or conductor bent to form a configuration having a plurality of sides or legs 70 19, 20, 21 and 22, to form a closed electric circuit or loop. One group of sides 21 and 22 are in one plane and the other group of sides 19 and 20 are in another plane at an angle to the plane of sides 21 and 22, as best 75 shown in Figs. 2 and 3. One side of each member namely, sides 19 coöperate to form a diverging spark gap and preferably a horn gap. It is understood that the configuration of the horn members 17 and 18 80 need not necessarily comprise four sides, the essential configuration being V-shaped members comprising an arcing horn or portion closed on itself such as sides 19 and 21 which are in a plane at an angle to the horizontal with means for completing a closed electric circuit or loop including said arcing horn or sides 19 and 21. Each horn member thereby broadly considered comprises an arcing portion or horn closed on itself to 85 form a closed circuited winding. To enable the arc to travel quickly along the arcing portions or sides 19 of the horn or short circuited members, I establish very intense magnetic fields in a direction along said 90 95 arcing portions to cause the arc to move along the arcing portions or horns 19 with great rapidity.

I am aware that all normal horn gaps with upward extending horns produce a 100 magnetic field which aids, to some extent, the heated currents of air in moving the arc up the horns. I am aware also that horns have been suggested comprising several turns to increase this magnetism but with 105 such a construction each of the turns is so far from the crater of the arc that the magnetic force applied to the arc is comparatively small. To obtain the tremendously rapid action of my device, many hundreds 110 and even several thousand amperes of circulating current are needed in the horn member to form the crater to feed the vapor into the arc.

In an ordinary horn gap, an arc from 115 metal melts far more metal than is necessary to feed the arc and this hot metal helps to ionize the immediate neighborhood and also furnish a wealth of conducting arc vapor. In my novel device, the magnetic fields along 120 each horn or arcing portions is in such a direction and of such an intensity and the contact of the arc on the horns is consequently moved with such great rapidity, that the melting of excess metal is avoided and 125 the quantity of vapor is rapidly diminished. The rapid lengthening of the arc and the fact that its contact with the metal is being

6 moved so rapidly, makes it impossible to feed the entire length of the arc with conducting vapor and consequently the arc is attenuated in cross section as it is drawn out and its 10 resistance is thereby proportionally increased.

To distinguish from the ordinary horn gap, it should be stated that the arc across an ordinary horn gap is not in general attenuated but is extinguished by some accidental movement of the hot rising vapors which throw a sheet of cold air through the arc stream. The arc breaks across again with the rise of current and voltage in the next 15 half cycle or is suddenly extinguished from a comparatively high value of current. In other words the attenuation is slight due to the feeding of the arc vapor through an almost vertical chimney of arc vapor.

20 To produce a magnetic field of the character I describe I make each of my horn members 17 and 18 with their arcing portions or horns 19 to constitute a closed electric loop or winding, each loop or circuit being inductively related to a winding in an external circuit such as the circuit through the switch. This I accomplish by connecting each loop through one or more turns on sides 20, for instance, as the secondary circuits of current 25 transformers 23 and 24 having primary circuits 25 and 26. The transformers 23 and 24 have their primaries 25 and 26, respectively, connected in the conductor 1 on each side of the switch. The current flowing 30 through the conductor 1 when the switch is closed, flows through the transformer primaries 25 and 26 and induces currents in their secondary circuits which comprise respectively the horn loops or members 17 and 18. The heavy currents traversing each of the horn members 17 and 18 set up strong electromagnetic fields which are in a direction to cause the arc, entering the fields to travel along the incline of the arcing portions or sides 19 with great rapidity. So 35 fast does the arc travel along the horns and become attenuated that the body of the arc between the two horn members 17 and 18 does not have time to rise appreciably, the path of the arc being usually an inverted arch in shape. Due to the fact that the magnetic field is stronger within the enclosure formed by the sides of each horn member and as the arc is moved so rapidly, the arc takes place substantially parallel to the arcing portions 19, the stronger field in the center of the horn inclosures tending to move the arc in that direction.

40 The arc is attenuated and extinguished in a few thousandths of a second and with such rapidity, due to the intense magnetic field produced along the arcing portions of the horn members, that the arc has no opportunity to bow out and be blown into adja-

cent phases. To prevent the arc from, under 45 any unusual circumstances, rising and arc- ing on sides 21 and 22, the sides of the horn members are located away from the arcing portions 19 and not vertically over the sides 19 as shown in Figs. 2 and 3.

The rapid attenuation of the arc causes its inherent resistance to automatically increase so that as the arc is extinguished its resistance is sufficient to prevent the formation of dangerous surges, as the extinguishing 75 force on the arc is always automatically about proportional to the value of current in the arc. When the arc is short, the force is great and when the arc is long and liable to be accidentally extinguished the force is 80 less, that is, it is proportional to the severity of the arc but does not tend to suddenly extinguish the arc from a high value of current and thereby cause a dangerous rise of potential. I thus utilize the inherent 85 resistance of the arc itself caused by its attenuation to prevent surge conditions without the use of any external resistance in series.

In cases where a weaker current is circu- 90 lated in the horn loops or members, I prefer to add, as a precautionary measure to prevent the arcs from being blown into adja- 95 cent phases, arc resisting means such as metal plates or grids 27 along the arcing 100 portions 19 of the horn members as shown, for instance, on horn member 18 in Fig. 1. These plates have a central opening 28 through which the horns 19 pass with clear- 105 ance, which openings insulate the plates 110 from the horns 19. A plurality of these grids are located along each horn 19 and are spaced apart and parallel to each other, each plate or grid being mounted at an angle to the axis of the horns 19 to form con- 115 stricted arc cooling chutes. The arc as it is moved up the arcing portions 19 passes through the openings 28 between the plates 27 and the horns. Should the arc, for any reason, bow outward, it engages the plates 120 110 115 120 27 and forms a plurality of arcs in series which act to quickly extinguish the arc by further attenuating it, the plates, at the same time, acting to cool the arc and prevent it from rising outside the plates and en- gaging adjacent phases. Instead of plates I may use, as best shown in Fig. 5, a member 28^a surrounding the arcing portion 19 of one or both horn members, which member may be of any shape but is preferably tubular in form.

It may often be desirable that the current 125 transformers 23 and 24 be normally inop- erative and not consuming current while the switch is closed. In Fig. 4 I have shown a modified form of switch in which the mov- able switch member 2 carries contacts 29 and 30 adapted to coöperate with contacts

31 and 32 respectively, to close a shunt circuit about the primary 25 of current transformer 23. These coöperating contacts 29, 31, and 30, 32, are arranged to separate on the initial opening movement of the switch member 2 to open the shunt circuit about the primary 25 an instant before the switch member breaks engagement with fixed contacts 3, so that the transformer 23 is rendered operative to produce a dense field around the horn member 17 as the switch opens. In like manner, I provide contacts 33 and 34 carried by a member 35 which is pivotally supported on the actuating member 6 and arranged when the switch opens to be likewise moved to break engagement with coöperating contacts 36 and 37, respectively, to open the shunt circuit about the primary 26 of transformer 24. The opening of the shunt circuits about both transformers 23 and 24 takes places simultaneously to produce a strong magnetic field in both horn members 17 and 18 as the switch opens. The operation of member 35 does not affect the circuit through the switch as I provide a flexible connection or conductor 38 between the switch and transformer 24.

It is understood that my novel arc extinguishing or attenuating device is not restricted in its use to extinguishing arcs produced by the opening of an electric switch but may be used by itself as an exceedingly quick acting horn gap lightning arrester, the arc occurring between the horn members 17 and 18 being quickly extinguished in the manner already described. It will also be understood that both the arcing portions of the horn members 17 and 18 constituting my arc extinguishing device may not be portions of closed electrical circuits or loops but one may be a part of such a circuit and the coöperating arcing portion may be a horn of ordinary type.

My invention may be embodied in other forms than that shown and described and I therefore do not wish to be restricted to the precise construction shown but intend to cover by the appended claims all changes and modifications which are within the scope 50 of my invention and will be apparent to those skilled in the art.

What I claim as new and desire to secure by Letters Patent of the United States, is:

1. The combination with an electric switch, of arc extinguishing means comprising coöperating members having portions coöperating to form a horn gap and adapted to take the arc as said switch opens, said coöperating members constituting closed electric circuits, and means inductively related to each of said closed electric circuits for inducing therein heavy electric currents in a direction to cause an intense magnetic field along the portions constituting said

horn gap whereby the arc formed on said portions is carried rapidly along said portions and attenuated.

2. The combination with an electric switch, of arc extinguishing means comprising arcing horns coöperating to form a horn gap, said horns constituting portions of closed circuited members inductively related to the circuit through the switch in a manner to cause a heavy induced current to traverse said closed circuited members and produce an intense magnetic field along said horns in such a direction that the arc travels with great rapidity along said horns and is quickly attenuated.

3. The combination with an electric switch, of an arc extinguishing device comprising two coöperating members each forming a conducting loop having a plurality of sides, one side of one loop coöperating with a corresponding side of the other loop to form arcing portions of a horn gap, an electrical winding on each side of said switch in the circuit of said switch coöperating with the loops constituting said arcing portions to form transformers, the windings of said transformers having such a relation that the current traversing said loops produces an intense magnetic field along said arcing portions acting to move said arc rapidly along said portions to attenuate it.

4. The combination with a movable switch member, of means for extinguishing the arc as said switch member opens comprising two closed circuited members having coöperating diverging portions adapted to form a spark gap, means for positively carrying the arc formed as said switch opens to said diverging portions of said closed circuited members, means responsive to the current through the switch for inducing a heavy current in each of said closed circuited members in a direction such that an intense magnetic field is produced along said diverging portions and within the inclosure of said closed circuited members to cause the arc across said gap to travel rapidly along said diverging portions and substantially parallel to said portions.

5. The combination with a movable switch member, of a horn gap device comprising two closed circuited conducting members provided with portions coöperating to form a horn gap, transformers having primary windings connected in the circuit through said switch member, said closed circuited members forming the secondaries of said transformers and traversed by a heavy induced current whereby an intense magnetic field is produced along said portions thereof forming said horn gap, means operatively related to said switch member

for short circuiting the primaries of said transformers while said switch member is closed and for opening said short circuits prior to the opening of said switch member.

5 6. The combination with a movable switch member, of arc extinguishing means coöperating therewith comprising two short circuited members having portions coöperating to form a horn gap, means responsive to the current through the switch for inducing a heavy current in said short circuited members in a direction to cause the magnetic field set up on said portions forming the horn gap to rapidly attenuate the 10 arc, and a member carried by said switch member and coöperating with the arcing portions to carry the arc formed as said switch member opens to said arcing portions.

15 7. An arc extinguishing device comprising coöperating members spaced apart to form a spark gap, each of said members consisting of a conductor bent to form a configuration having a plurality of sides and constituting a closed electric circuit, means inductively related to each of said closed circuits for inducing therein a current forming an intense magnetic field in a direction to lengthen and attenuate the 20 arc across said spark gap with great rapidity.

8. An arc extinguishing device comprising coöperating members having portions thereof adapted to receive an arc and coöperating to form a horn gap, each of said coöperating members forming a closed electric circuit inductively related to an external circuit whereby the magnetic field set up by the current induced in said coöperating members 25 acts to move the arc along the arcing portions of said members with great rapidity.

9. An arc extinguishing device comprising coöperating members having portions thereof adapted to receive an arc and coöperating to form a horn gap, coöperating portions for producing in each of said members a closed electrical loop, means responsive to the current through the switch for inducing currents in the loops comprising said coöperating members in a direction to cause the magnetic fields around the arcing portions of said coöperating members to be of an intensity to rapidly move the arc along 30 said portions and attenuate it.

10. An extinguishing means comprising coöperating members each constituting a closed electrical circuit and having arcing portions thereof coöperating to form a horn gap, transformers having primaries connected in an external circuit, said coöperating members forming the secondaries of said 35 transformers and arranged to produce a magnetic field along the arcing portions

thereof in a direction and of an intensity to cause the arc to be attenuated with great rapidity.

11. An arc extinguishing means comprising a horn gap device, each horn being closed on itself to form a closed circuited winding, 40 coöperating windings in inductive relation to said closed circuited windings and adapted to cause heavy induced currents to traverse said closed circuited windings to produce an intense magnetic along each horn 45 in a direction to rapidly attenuate the arc and thereby automatically increase its inherent resistance whereby the arc is extinguished quickly and without producing detrimental surges.

12. An arc extinguishing device comprising coöperating arcing members each consisting of a continuous conductor bent to form a configuration having a plurality of sides, one side of each member coöperating 50 to form a diverging spark gap, means for inducing a current in said continuous conductors to produce a magnetic field along the sides forming said spark gap having an intensity and a direction to cause an arc 55 between said members to be moved quickly along said sides and to be rapidly attenuated.

13. An arc attenuating device comprising two conductors forming closed loop 60 members of a configuration having a plurality of sides, one side of each member coöperating to form a horn gap, means inductively related to each member for causing a heavy current to flow through said 65 closed loop members to produce a magnetic field along said sides constituting said horn gap such that an arc across said horn gap is rapidly drawn out in a direction substantially parallel to said sides and attenuated, 70 whereby the attenuation of the arc automatically increases its resistance until it is extinguished.

14. An arc attenuating device comprising coöperating horn members adapted to 75 form a horn gap, each of said horn members consisting of a conductor bent to form a closed electrical circuit, means inductively related to each horn member for causing a heavy current to pass through the closed 80 electrical circuits of said members such that the intense magnetic field produced by said horn members acts to so quickly lengthen the arc that it is rapidly attenuated and extinguished without setting up detrimental 85 surges.

15. A protective device comprising two substantially V-shaped members spaced apart and having their sides in a plane at an angle to the horizontal, one side of each 90 member being an arcing portion and coöperating to form a diverging spark gap, means coöperating with said V-shaped mem-

- bers to produce closed circuited windings including said members, inductive means for causing a heavy induced current to flow in said closed circuited windings to produce an 5 intense magnetic field in a direction to rapidly attenuate the arc, whereby the resistance to the flow of current through the arc is rapidly increased until the arc is extinguished.
- 10 16. A protective device comprising co-operating arcing members each formed of a conductor bent in a configuration having a plurality of sides, one group of sides in a plane at an angle to the plane of the first 15 group of sides, said plurality of sides being arranged to form a closed circuited secondary of a transformer, one side of each member forming an arcing horn, each arcing horn being traversed by the current in 20 said closed circuit secondary to produce an intense magnetic field in a direction to attenuate the arc occurring across said horns with great rapidity.
17. An arc extinguishing means comprising 25 two short circuited members provided with sides co-operating to form a diverging spark gap, windings in inductive relation to said short circuited members and so arranged that the currents induced in said 30 closed circuited members produce intense magnetic fields along said sides constituting the horn gap in a direction to attenuate the arc with great rapidity.
18. A protective device comprising arcing 35 horns forming a horn gap, means whereby said horns are each adapted to form a portion of a closed electrical loop, means in inductive relation to each loop for causing a current to traverse each loop and set up a 40 magnetic field on each horn, the currents in each loop being so related that the magnetic field along each horn is in a direction to cause the arc to be rapidly moved along said horns and attenuated.
- 45 19. A protective device comprising two co-operating members formed of a continuous conductor each member having four sides, two of said sides being in one plane and the other two sides being in a plane 50 at an angle to the plane of the first two sides, one side of each member co-operating to form a horn gap, transformers having said four sided members as secondary windings and with primary windings in an external circuit.
- 55 20. An arc extinguishing device comprising co-operating members adapted to form a closed electrical circuit and provided with arcing portions co-operating to form a horn gap, transformers having said co-operating members as short circuited secondary circuits whereby a heavy current flows along said arcing portions and magnetic fields are produced which move the arc along said
- portions with great rapidity to attenuate 65 and finally extinguish the arc.
21. An arc attenuating device comprising co-operating members provided with horns adapted to form a horn gap, said members forming closed electric circuits, a plurality 70 of plates mounted on said horns and provided with openings through which said horns pass, means inductively related to each of said closed circuits for inducing therein heavy electric currents forming magnetic fields along said horns in a direction 75 to rapidly attenuate the arc by drawing it along said horns through the openings in said plates.
22. An arc extinguishing device comprising 80 an arcing horn, said horn comprising a conductor bent to form a closed electric circuit, means inductively related to said closed electric circuit for causing heavy induced current to flow in said arcing horn, and a second 85 arcing horn co-operating to form a horn gap.
23. An arc extinguishing device comprising 90 a member constituting an arcing horn, said horn forming part of a closed circuited secondary of a transformer, arcing plates mounted along said horn and spaced apart to form constricted arc chutes, said arcing plates being provided with openings 95 through which said horn passes with clearance, and a second horn co-operating with said first mentioned horn to form a horn gap.
24. An arc extinguishing device comprising 100 a horn member forming a closed electric circuit and provided with an arcing portion, said horn member forming the secondary circuit of a transformer, whereby heavy induced currents are caused to flow in said horn member, and a co-operating arcing horn 105 forming with the arcing portion of said horn member a horn gap.
25. A device comprising two co-operating 110 closed circuited members spaced apart and provided with arcing portions co-operating to form a diverging spark gap, means inductively related to said closed circuited members for causing a heavy current to traverse said closed circuited member and form dense magnetic fields along said 115 arcing portions in a direction to attenuate the arc, and arc resisting means surrounding one of said arcing portions.
26. In combination with a circuit opening 120 device, means for extinguishing the arc formed as said device operates, comprising co-operative members having portions adapted to receive the arc and shaped to attenuate the same, and means inductively 125 related to said member for setting up magnetic fields along the arcing portions of said members in a direction to attenuate the arc with great rapidity.

27. In combination with a circuit opening device, arcing horns coöperating with said device to take the arc formed as said device operates, and means for setting up magnetic fields along said arcing horns in a direction to move the arc upwardly along said horns with great rapidity.
28. An arc extinguishing device comprising coöperative members spaced apart to form a horn gap, and means for causing magnetic fields to exist along said horn members in a direction to attenuate the arc with great rapidity.
29. A protective device comprising coöperating arcing members spaced apart to 15 form a diverging spark gap, means whereby said members are adapted to form portions of closed electrical circuits, means for causing a current to traverse these circuits and set up magnetic fields along said arcing 20 members in a direction to move the arc along said members with great rapidity.

In witness whereof, I have hereunto set my hand this 3rd day of June, 1916.

ELMER E. F. CREIGHTON.
